UNITED STATES PATENT OFFICE

2,462,611

SHOE OR BOOT DISPLAY DEVICE

Clarence M. Bye, Osseo, Wis.

Application June 5, 1947, Serial No. 752,809

4 Claims. (Cl. 211—34)

1

This invention relates to a shoe or boot display device.

An object of this invention is the construction of a simple and efficient device for supporting a boot or shoe or like foot wear in position for suitable display.

Another object of the invention is the construction of an efficient display device which can be easily applied to a suitable support for displaying shoes, boots, or the like.

A still further object of the invention is the construction of a display device comprising a minimum number of parts, and which is comparatively inexpensive to manufacture, and highly efficient in operation.

With the foregoing and other objects in view, my invention comprises certain novel constructions, combinations, and arrangements of parts as will be hereinafter fully described, illustrated in the accompanying drawings, and more particularly pointed out in the appended claims.

In the drawings:

Fig. 1 is a view in side elevation of a display device constructed in accordance with the present invention, while

Fig. 2 is a top-plan view of the same.

Fig. 3 is a central, vertical sectional view taken on line 3—3, Fig. 2.

Fig. 4 is a perspective view of the sliding plate.

Fig. 5 is a fragmentary perspective view of the display device.

Fig. 6 is a vertical, central sectional view of another embodiment of this invention, while

Fig. 7 is a perspective view of the sliding plate thereof.

Referring to the drawings, in which the preferred invention is shown in Figs. 1 to 5, I designates the elongated body which is in the nature of a strip of metallic material. The body 1 has an elongated slot 2, Fig. 3, and is provided at its inner end with the primary jaw 3. An auxiliary jaw 4 has an extension 5, which extension is riveted to the elongated body 1 at 6, 6, Fig. 2.

A clamping lip 7 is bent outwardly from the inner end of primary jaw 3, and this lip is provided on its inner face with a piece of felt, or like material, 8.

A sliding plate 9 is mounted upon the body 1. This plate 9 is provided at its inner end with an upstanding clamping flange 7a; flange 7a has a piece of felt or like material 8a on its inner face, corresponding to the piece of felt 8. Sliding plate 9 is provided at its outer end with a downwardly extending extension 10 which terminates in an arrow-like head 11. Extension 10 works

2

within the elongated slot 2. The head 11 engages the under face of the elongated body 1, and positively retains the sliding plate 9 against accidental displacement. When it is desired to assemble plate 9 with body 1, plate 9 is turned at right angles to body 1 as shown by dotted lines A, Fig. 2. Then after the arrow-like head 11 has been placed through slot 2, the plate is turned parallel with body 1, whereupon the sliding plate 10 is locked in position upon the body. The sliding plate has a stop-tit 12 struck down; this stop-tit 12 normally is in slot 2, striking against the inner end of the slot, thereby limiting the movement of the sliding plate towards the inner end 15 of the elongated body 1; although the space between the lip 7 and flange 7a is always sufficient to receive the smallest heel. A depending hook 13 is also struck down from plate 9; this hook 13 extends through slot 2. A depending hook 14 is struck down from the auxiliary jaw 4. On hooks 13 and 14 is mounted the coil spring 15; this coil spring normally exerts an inward pull on the sliding plate 9. Therefore, the sliding plate can be moved towards the outer or lower end of elongated body 1, against the action of spring 15, sufficient to allow of any size heel being placed between the felt-carrying lip 7 and flange 7a. In the embodiment shown in Figs. 6 and 7, the structure of the display device is substantially the same as in the preferred embodiment, Figs. 1 to 5. In this embodiment slidable plate 9a is provided with a spur 16 on the clamping flange 7a, this spur 16 being provided for engagement with the heel of the boot or shoe mounted on the device. The sliding plate 9a is provided with the extension 10 and head 11 at the inner end of the plate, contiguous to the upstanding flange 7a. The depending hook 13 in this embodiment is near the outer or lower end of the sliding plate 30 9a. Therefore, the coil spring 15 is mounted on the hook 14 and hook 13. Consequently, the functioning of the parts in this embodiment is the same as that in the preferred embodiment.

The felt covering the heel-contacting surfaces 45 of the preferred embodiment gives sufficient frictional action, without injury to the heel. If desired the spur 16 may be used, as it does not penetrate the heel very far, thereby not injuring the heel, and any penetration will be on the inner face of the heel, without detracting from the sales point of view.

While I have described the preferred embodiments of my invention and illustrated the same in the accompanying drawings, certain minor 50 changes or alterations may appear to one skilled

in the art to which this invention relates during the extensive manufacture of the same, and I, therefore, reserve the right to make such changes or alterations as shall fairly fall within the scope of the appended claims.

What I claim is:

1. In a device of the class described, the combination of a body provided at its inner end with a support clamp, said body provided with a slot, a slidable plate on said body over said slot, means extending from said slidable plate through said slot and normally holding said slidable plate upon said body, a spring and means connecting the inner end of said spring to said support clamp, means connecting the outer end of said spring through said slot to said slidable plate, and said body and slidable plate provided with heel-clamping means.

2. In a device of the class described, the combination of an elongated body, said body provided at its inner end with a support clamp, said support clamp provided with a depending hook, a slidable plate on said body, said body provided with an elongated slot, said slidable plate provided near its inner end with an extension in said slot, a head on said extension, said slidable plate provided at its outer end with a hook extending through said slot, a yielding member on said depending hook, and said body and slidable plate provided with heel-clamping means.

3. In a device of the class described, the combination of an elongated body provided with an elongated slot, said body provided at its inner end with a support clamp and with a clamping lip, a plate slidably mounted on said body, said

plate provided with an extension in said elongated slot, a head formed on said extension, said plate provided with a depending hook, in said slot, said support clamp provided with a depending hook, and a spring mounted on said depending hook to urge the plate towards the lip.

4. In a device of the class described, the combination of an elongated body provided with an elongated slot near its inner end, said elongated body provided at its inner end with a primary jaw, said primary jaw provided with a struck-out clamping lip, an auxiliary jaw extending from the inner end of said elongated body, said auxiliary jaw provided with a depending hook, a plate slidably mounted on said elongated body, said plate provided with a depending stop-tit extending into said slot, said slidable plate provided with a depending hook near its center, said depending hook mounted in said elongated slot, said slidable plate provided at its outer end with an extension in said slot, said extension provided with an arrow-like head, said head normally engaging the under face of said elongated body, and a coil spring mounted on said depending hook to urge the plate towards the lip.
